Term of patent 14 years

(Cl. D64—11)

FIG. 1

FIG. 2

FIG. 3

FIG. 4

FIG. 5

FIG. 1 is a front perspective view of a portable typewriter, showing our new design as it appears with the cover in closed position;

FIG. 2 is a similar view thereof as it appears with the cover in open position;

FIG. 3 is a left side elevational view thereof as it appears with the cover removed;

FIG. 4 is a front elevational view thereof; and

FIG. 5 is a rear elevational view thereof.

The design is characterized by front and rear walls which curve outwardly and upwardly from a base; by side walls which curve outwardly from front to rear and outwardly and upwardly from said base to continue upwardly in a substantially vertical manner; by a lip disposed along said front and rear walls in a horizontal fashion and along said side walls, front to back, with a sharp rise and a gradual decline; by a top which curves inwardly and upwardly from said lip and which also forms an edge to frame the typewriter keyboard; and by a cover which, in box like fashion conforms to the contour of the top and sides, and which terminates in an edge having the configuration of said lip.

We claim:

The ornamental design for a portable typewriter, as shown and described.
